CLAIM

The ornamental design for a sink strainer and stopper, as shown and described in the Figures.

DESCRIPTION

FIG. 1 is an isometric view of the sink strainer and stopper in an open state;

FIG. 2 is a front elevation view of the sink strainer and stopper in the open state;

FIG. 3 is a side elevation view of the sink strainer and stopper in the open state;

FIG. 4 is a cross-sectional view of the sink strainer and stopper in the open state taken along line FIG. 4-FIG. 4 in FIG. 2; FIG. 5 is a top side view of the sink strainer and stopper in the open state;

FIG. 6 is a bottom side view of the sink strainer and stopper in the open state;

FIG. 7 is an isometric view of the sink strainer and stopper in a closed state;

FIG. 8 is a front elevation view of the sink strainer and stopper in the closed state;

FIG. 9 is a side elevation view of the sink strainer and stopper in the closed state; and,

FIG. 10 is a cross-sectional view of the sink strainer and stopper in the closed state taken along line FIG. 10-FIG. 10 in FIG. 8.

The broken line showing is included for the purpose of illustrating portions of the article and forms no part of the claimed design.

1 Claim, 6 Drawing Sheets
